ABSTRACT OF THE DISCLOSURE

Two push-pull-connected semiconductor elements, such as transistors or controlled rectifiers, are provided with a predominantly reactive input circuit including a condenser so connected in a feedback path that, upon incipient conduction through one semiconductor element, a charging current flows through the input of that element to drive it to instant saturation. The charging current, decreasing first rapidly and then more gradually from an initial peak, reverses at the instant of switchover to drive the other semiconductor element to its saturated state.

My present invention relates to an oscillator of the type wherein two three-electrode semiconductor elements, such as transistors or controlled rectifiers, are connected in push-pull so as to become alternately conductive to generate a substantially rectangular output current which may be applied directly to a load, with or without rectification (e.g. in accordance with my prior Pat. No. 2,968,738), or may be converted into a sinusoidal load current (e.g. as disclosed in my prior Pat. No. 3,026,486).

In order to produce the desired square-wave output, such oscillators heretofore made use of saturable transformers with special feedback windings designed to deliver a suitable switching voltage to the inputs of the semiconductor elements. Such saturable transformers are relatively expensive and are also wasteful in operation, owing to the hysteresis losses introduced thereby. When the state of conductivity of the semiconductors is reversed at high load current, considerable switching losses occur in addition.

It is, therefore, the principal object of my present invention to provide an improved oscillator of this general type which avoids the aforesaid drawbacks.

Another important object of my invention is to provide an oscillator of the type set forth in which, at the moment of switchover, the semiconductor elements are instantly driven to full saturation and cut off, respectively, even at high operating frequencies so that the resulting output current approximates a purely rectangular wave form.

Particularly when transistors are used as the semiconductor elements, a certain lag is generally encountered between the application of an unblocking voltage to the base/emitter circuit and the appearance of an appreciable flow of collector current; similarly, the removal of the unblocking voltage is followed only after a certain delay by the complete restoration of the nonconductive state. This phenomenon may be linked to the effect of a virtual capacitance connected across the input electrodes of the transistor, such virtual capacitance being substantially greater than the actual interelectrode capacitance between base and emitter and being due to the finite time required for the injection of a sufficient quantity of minority carriers into the semiconductor and for the subsequent sweep-out of these carriers. Thus, it is a more particular object of my invention to provide an oscillator circuit adapted to generate, at the instant of incipient conduction of one of two paired transistors, a large base current through this transistor to overdrive the latter for a short fraction of a

2

cycle whereby the necessary population of minority carriers is made available, the base current thereupon decaying rapidly to a sustaining level which maintains the transistor in saturation by supplying enough carriers to compensate for those lost through recombination; conversely, at the end of the half-cycle, the voltage applied to the base is to be abruptly reversed so that the remaining minority carriers are quickly removed and the hitherto conductive transistor is restored to its nonconductive state while its mate goes to saturation, possibly after some controllable delay.

These objects are realized, pursuant to my present invention, by the provision of an input circuit for the two push-pull-connected semiconductor elements which includes one or more condensers in cascade with the control electrode (e.g. base) and one main electrode (e.g. emitter) of each semiconductor element, this input circuit being regeneratively coupled to the common output circuit of the two elements so that these two input electrodes are traversed, upon incipient conduction, by a charging current which instantly drives the element to saturation and which decays first rapidly and then more gradually from an initial peak until a point is reached at which the condenser begins to discharge, thereby firing the other semiconductor element which instantly saturates as the discharge current is stepped up by the feedback into a charging current of opposite polarity with reference to the previous charging current.

With semiconductors whose input circuit loses control over the output current once conduction has been established, as is true of solid-state controlled rectifiers, a commutating condenser or equivalent circuitry may have to be provided to cut off the first semiconductor upon incipient current flow through the second semiconductor; with other types of three-electrode semiconductors, such as the various kinds of transistors, the cutoff occurs automatically as soon as the input current drops below the sustaining level.

The term "connected in cascade," as applied above to the input electrodes and the associated condenser of my improved oscillator, implies that this connection may be direct (the condenser lying in series with these input electrodes) or may include any interposed transformers whereby not the condenser itself but its equivalent capacitance (as reflected from the primary into the secondary circuit) appears in series with the semiconductor input. In either case, I prefer to make the input circuit predominantly reactive so as to minimize the dissipation of feedback energy.

A modulating signal may be impressed upon the input circuit to control the onset of the flow of charging current and/or the time when this current reaches the cutoff level. Such a modulating signal may act upon any suitable variable impedance inserted in the input circuit or in the feedback path, e.g. an auxiliary transistor or a phase shifter; the signal itself may be derived from the oscillator output, for the purpose of stabilizing the operating frequency and/or the mean output energy as generally disclosed in my prior Pat. Nos. 3,088,075 and 3,207,931, or may be externally generated to produce a varying output.

The above and other features of my invention will be described in greater detail with reference to the accompanying drawing in which:

65 FIGS. 1–11 are circuit diagrams illustrating various oscillators embodying the invention;

FIGS. 12 and 13 show modified input circuits to be used with some of the oscillators of the preceding figures; and

FIGS. 14 and 15 are two sets of explanatory graphs.

In FIG. 1 I have illustrated an oscillator 10 comprising a pair of transistors 11, 12 (here shown to be of the

NPN type) with their emitters connected to a negative bus bar 13, their collectors connected across the primary winding 14 of a nonsaturable output transformer 15 whose midpoint is tied to a positive bus bar 16, and with their bases interconnected by a choke 17 having a center tap returned to bus bar 13. Transformer 15 has a main secondary winding 18, connected across a load 19, and a feedback winding 20 connected across choke 17 in series with a capacitor 21. Another condenser 22 is bridged across the choke 17.

A starting switch 23 is shown included in bus bar 13. Upon closure of this switch, negative potential is connected to the emitters of transistors 11, 12 and, via respective halves 17', 17'' of choke 17, to the bases thereof. The slight voltage drop across these choke halves makes the emitters somewhat more negative than the bases so that the transistors tend to become conductive, one of them generally starting to conduct before the other. The collector current of this one transistor—say, element 11—then traverses the corresponding half of primary winding 14 and induces a feedback voltage in secondary winding 20 which initiates the flow of a charging current through capacitor 21, the base and emitter of transistor 11, bus bar 13 choke portion 17', and a return lead 24. The polarity of this charging current is such as to block the other transistor 12 and to drive the transistor 11 toward full saturation, with resultant intensification of the charging current which thereby reaches a peak almost immediately upon closure of switch 23. Through proper proportioning of the reactive network 17, 21, 22 I can delay the flow of a substantial part of this charging current through the other half 17'' of choke 17 for a fraction of a cycle sufficient to bring about the saturation of transistor 11; thereafter, the current flow through the input electrodes of this transistor will be reduced as the condenser 21 discharges partly through the base of this transistor and partly through the choke 17. When the magnitude of the base current drops below the conduction-sustaining level, transistor 11 cuts off and the charge built up on condenser 21 causes the flow of a reverse current from that condenser through winding 20, lead 24, base and emitter of transistor 12, bus bar 13 and choke portion 17''; this reverse current is intensified by the inverted feedback voltage now induced in winding 20 as the collector current from transistor 11 disappears. Transistor 12 now begins conducting and generates an oppositely directed current flow in transformer primary 14 so that the feedback voltage increases and gives rise to a reversed charging current which now drives the transistor 12 to saturation. In this second half-cycle the transistor 12 is energized in the same manner as previously transistor 11, a further switch-over occurring upon the condenser current dropping to the cutoff level. In this manner, free-running oscillations of a predetermined frequency are generated by the system of FIG. 1; the frequency of these oscillations could be varied, if desired, by a readjustment of any of the reactances 17, 21, and 22. Condenser 22 may be omitted, particularly if it is not desired to vary the tuning of the reactive network to any major extent.

The aforescribed mode of operation of oscillator 10 has been illustrated in FIG. 14 where graphs (a) and (b) show the collector currents I_{11} and I_{12} of transistors 11 and 12, respectively; graph (c) illustrates the charging current I_{21} of capacitor 21 whereas graph (d) represents the load current I_{19} . It will be noted that the condenser current I_{21} sharply peaks at the instants of switch-over, thereafter decaying to the respective cutoff level L_{11} and L_{12} ; the switch-over substantially coincides with the instants of zero load current I_{19} so that switching losses are minimized.

In FIG. 2 I have illustrated an oscillator 10a wherein the transistors 11, 12 of FIG. 1 have been replaced by controlled rectifiers 11a, 12a. The feedback circuit of this oscillator has also been modified in that the winding 20a

5 in series with capacitor 21a is now connected across the primary of an input transformer 29a whose secondary replaces the choke 17 of FIG. 1 and is connected across the gates of the controlled rectifiers. The anodes of rectifiers 11a, 12a are connected across primary 14a of output transformer 15a which is bridged by a commutating condenser 54a. FIG. 2 also shows the midpoint of the input inductances, i.e. of the secondary of transformer 29a, connected not directly to negative bus bar 13a but to a 10 point of more positive potential formed by a voltage divider 25a, 26a which spans the two bus bars 13a and 16a. Starting switch 23a is here shown inserted in the positive bus bar 16a. The cathodes of elements 11a and 12a, like the emitters in the preceding embodiment, are 15 joined together by a conductive connection forming an extension of the negative bus bar.

Finally, FIG. 2 indicates the possibility of energizing the load 19a from the secondary 18a of output transformer 15a with sinusoidal rather than rectangular current by using a combination of series-resonant and parallel-resonant networks 27a, 28a as disclosed and claimed in my aforementioned prior Pat. No. 3,026,486.

The operation of oscillator 10a is generally similar to that of oscillator 10 in FIG. 1, closure of switch 23a resulting in incipient conduction of one of the controlled rectifiers (say, 11a) which causes the flow of a charging current for condenser 21a through the primary of transformer 29a and of a balancing current through the secondary thereof through the input (gate/cathode) circuit of this controlled rectifier via bus bar 13a, resistor 25a and the center tap of the secondary to drive this semiconductor to saturation. After the charging current has decayed and condenser 21a begins to discharge, controlled rectifier 12a starts to conduct, the resulting switch-over applying an extinction potential to the anode of rectifier 11a via commutating condenser 54a; the voltage divider 25a, 26a is so dimensioned that the biasing voltage impressed upon the gates of the controlled rectifiers is barely sufficient to initiate conduction in the absence of a feedback current through condenser 21a.

FIG. 3 shows an oscillator 10b whose transistors 11b and 12b, here shown to be of the PNP type, are connected across a center-tapped choke 17b bridged by the series combination of condenser 21b and the secondary winding of a feedback transformer 29b which has two primary windings connected in series with the emitters of transistors 11b and 12b. FIG. 3 also shows, by way of example, a common-collector circuit wherein the negative bus bar 13b is tied to the collectors of both transistors 50 whereas the positive bus bar 16b is connected (by way of switch 23b) to the midpoint of the primary 14b of output transformer 15b and thence to the two emitters via the aforementioned primary windings of feedback transformer 29b. Bus bars 13b and 16b are shown bridged by a voltage divider which differs from that of FIG. 2 in that the resistor 26a of the preceding embodiment has been replaced by the reverse resistance of a diode 26b in series with resistor 25b; diode 26b is shunted by a condenser 30b. With switch 23b open, condenser 30b charges to the 55 terminal voltage of the D-C source connected across these bus bars so that the bases of transistors 11b and 12b are driven sharply negative, with reference to their emitters, when the switch 23b is closed whereby one transistor is immediately turned on; condenser 30b then discharges at 60 a rate determined by the time constant of the network 25b, 26b, 30b, this time constant being advantageously equal to several operating cycles of the oscillator 10b.

In FIG. 4 I have illustrated another modification wherein in an oscillator 10c comprises a pair of transistors 11c, 12c connected across a secondary of a feedback transformer 29c in the general manner of the controlled rectifiers 11a and 12a of FIG. 2. Transistors 11c and 12c, here of the NPN type, have their bases tied together and connected to a tap on a voltage divider which is generally similar to that of FIG. 3 but wherein the ordinary diode 26b has

been replaced by a Zener diode 26c in series with resistor 25c and in parallel with condenser 30c. This arrangement reduces the initial charge on the starting condenser 30c to a value intermediate the potentials of bus bars 13c and 16c. Starting switch 23c is here shown inserted in bus bar 13c which leads to the midpoint of the secondary of feedback transformer 29c, the primary of this transformer being connected across the collectors of transistors 11c and 12c in series with condenser 21c. In this embodiment, therefore, the capacitance of the input condenser does not lie directly in series with the input electrodes (emitters) of the two transistors but, as in the circuit arrangement of FIG. 2, is reflected into the input circuit of these semiconductors through the intervening feedback transformer. The output transformer has been shown at 15c.

In FIG. 5 I have illustrated the possibility of using two transistors of opposite conductivity types, i.e. an NPN transistor 11d and a PNP transistor 12d, in an oscillator 10d according to the invention. Negative bus bar 13d is connected to the emitter of transistor 11d and, via a primary winding 14d' of output transformer 15d, to the collector of transistor 12d; positive bus bar 16d (which includes the start switch 23d) is similarly connected to the emitter of transistor 12d and, via another primary winding 14d' of transformer 15d, to the collector of transistor 11d. The input circuit of transistor 11d includes a connection from a relatively negative tap on a voltage divider 25d to the base of this transistor through a secondary winding of feedback transformer 29d; the input circuit of transistor 12d includes a connection from a relatively positive tap of voltage divider 25d to the base of this transistor through another secondary of transformer 29d. The primary of transformer 29d is connected, as in the embodiment of FIG. 2, to an auxiliary winding 20d of output transformer 15d in series with capacitor 21d.

Naturally, the secondaries of feedback transformer 29d must be so poled that the voltages induced therein, upon a charging of condenser 21d in one sense or the other, will render only one of the two transistors conductive.

In FIG. 6 I have illustrated an oscillator 10e with two pairs of transistors 11e', 12e', 11e'', 12e'' connected in a bridge circuit, the collectors of transistors 11e', 11e'' being tied to bus bar 16e at one corner of the bridge while the emitters of transistors 12e', 12e'' are tied to bus bar 13e at the diagonally opposite corner. Connected in the other diagonal of the bridge are the primary of output transformer 15e and, in parallel therewith, the primary of feedback transformer 29e lying in series with capacitance 21e. Feedback transformer 29e has four secondary windings connected across the inputs of the respective transistors. Starting switch 23e is shown inserted in bus bar 16e.

In the operation of the oscillator 10e, condenser 21e is alternately charged through the diagonally opposite transistors 11e', 12e'' and the similarly paired transistors 12e', 11e''. The operation is otherwise analogous to that of the circuit of FIG. 4.

FIG. 7 shows, basically, an oscillator 10f which is similar to oscillator 10c of FIG. 4 (apart from using a common-emitter connection) and further includes an auxiliary transistor 31f inserted in the connection between bus bar 13f and the midpoint of the secondary of feedback transformer 29f. Transistor 31f, corresponding to a control signal from a source diagrammatically indicated at 32f, constitutes a variable impedance in the input circuit of transistors 11f and 12f which modifies the charging rate of condenser 21f represented by the curve I_{21} in graph (c) of FIG. 14. This causes the switchover between positive and negative half-cycles to occur at shorter or longer intervals, thereby changing the frequency of the pulse trains I_{11} , I_{12} illustrated in graphs (a) and (b) of FIG. 14. In this embodiment it is not necessary to provide a starting switch since the oscillator may be

started and stopped by the application of a suitable biasing voltage to transistor 31f.

An analogous arrangement has been illustrated in FIG. 8 where the oscillator 10g, similar to that of FIG. 1, has an input transformer 33g with a primary connected across signal source 32g and with a secondary inserted in the connection between bus bar 13g and the midpoint of choke 17g; control signals applied to transformer 33g again serve to modify the charging rate of condenser 21g, thereby increasing or reducing the operating frequency of the oscillator.

As illustrated in FIG. 9, I may also control the output of the oscillator by introducing a variable phase shift in the feedback path. Thus, the oscillator shown in FIG. 9 comprises two substantially identical oscillation generators 10h' and 10h'', both similar to the oscillators 10 and 10g of FIGS. 1 and 8, which differ from each other only in that the choke 17h'' of generator 10h'' is split into two halves separated by the secondary of a feedback transformer 33h whose midpoint is returned to the negative bus bar 13h; the primary of transformer 33h is connected across a special pick-up winding 34h of output transformer 15h' of oscillation generator 10h', with interposition of a phase shifter 35h having a control input connected to a lead 36h for the application of a modulating signal from a source not shown. The secondaries 18h' and 18h'' of the output transformers 15h' and 15h'' of the two oscillation generators are connected in aiding relationship across a load 19h. Bus bars 13h and 16h are common to both transistors, a starting switch 23h being included in bus bar 13h.

In operation, oscillator 10h' functions in the aforescribed manner to generate a load current similar to that shown at I_{19} in graph (d) of FIG. 14; oscillation generator 10h'' produces a similar load current whose timing, however, depends on the phase shift, if any, introduced by the circuit 35h. Thus, if this phase shift is zero, transistor 11h' or 12h'' of generator 10h'' will be triggered into conduction substantially concurrently with transistor 11h' or 12h' of generator 10h' by the biasing signal developed across transformer 33h so that the output currents in windings 18h' and 18h'' will be in phase. If, however, a finite phase shift is introduced by the control circuit 35h, the two oscillation generators 10h' and 10h'' will operate in the same rhythm but with staggered periods so that the magnitude of the combined load current will decrease; with a phase shift of 180°, this load current disappears completely. If the coils 18h' and 18h'' were connected in series-opposing relationship, the load current would be zero in the absence of a phase shift and would progressively increase with the angle of shift of phase shifter 35h.

FIG. 10 shows an oscillator 10i, similar to that of FIG. 7, whose control circuit includes an auxiliary transistor 31i in series with the output diagonal of a rectifier bridge 37i whose input diagonal lies in series with the primary of feedback transformer 29i as well as feedback winding 20i and condenser 21i. An input signal from a source 32i applied to transistor 31i will therefore create a bias to alter the operation of the oscillator in essentially the manner described in connection with FIG. 7.

The signal source 32i could be controlled by the oscillator output in a manner tending to stabilize the average load current. Thus, with the aid of suitable circuitry as described, for example, in my prior Pat. Nos. 3,088,075 and 3,207,931, I may derive from the load current I_{19} (FIG. 14) a train of rectangular pulses whose width varies in accordance with the charge of an ancillary condenser 38i which is connected via a rectifier network 39i across another secondary 40i of output transformer 15i; the source 32i may in this case include a magnetic amplifier controlled, as in my aforementioned prior patents, through a lead 36i which may include a Zener diode 41i.

Reference will now be made to FIG. 15 for an explanation of the manner in which rectangular pulses gen-

erated by the source $32i$, in response to the charge on condenser $38i$ and therefore to the magnitude of the load current in output winding $18i$, stabilizes this magnitude by introducing a compensatory bias into the feedback circuit of oscillator $10i$. As shown in graph (a) of FIG. 15, the control pulses P_{32} are of varying width, it being assumed that this width is substantially proportional to the charge on condenser $38i$. Since these pulses are of negative polarity so as to block the transistor $31i$, they interrupt the charging circuit of condenser $21i$ for longer or shorter periods at the beginning of each half-cycle, i.e. upon switchover from transistor $11i$ to transistor $12i$ or vice versa. These transistors are therefore triggered into saturation after varying delays δ_{11} , δ_{12} , following cutoff of the respective companion transistor, as illustrated in graph (b) of FIG. 15. The delayed turn-on of these transistors therefore shortens the time interval available for the flow of charging current I_{21} , graph (c), this interval being terminated by the occurrence of the next blocking pulse P_{32} which cuts off the conductive transistor and preserves the charge on condenser $21i$ until the pulse disappears whereupon the condenser begins to discharge and to acquire a reverse charge as previously described. The result is a load current I_{19} which, as shown in graph (d) of FIG. 15, has a generally rectangular wave shape with pulses of varying width. The substantial constancy of the fundamental frequency of wave I_{19} may be insured by the use of a resonant load circuit as illustrated in FIG. 2 and described in my prior Pat. No. 3,026,486.

The control pulses applied to transistor $31i$ need not occur at the beginning of each half-cycle but may be supplied in a more or less random manner from an extraneous source. Conversely, a synchronizing circuit as shown at $36i$ in FIG. 10 could also be used to control the signal sources $32f$, $32g$ of FIGS. 7 and 8 or the phase shifter $35h$ of FIG. 9.

FIG. 11 shows an oscillator $10j$ whose choke $17j$ is designed as an autotransformer which steps down the switching potential applied to the bases of transistors $11j$, $12j$, the collectors of these transistors being connected across the extremities of the autotransformer $17j$ through respective capacitors $21j'$ and $21j''$. The system operates otherwise in the manner of oscillator 10 of FIG. 1.

FIG. 12 shows a choke $17k$ which operates as a step-up autotransformer winding whose terminal voltage is impressed upon a pair of Zener (i.e. avalanche-type) diodes $42k$, $43k$ connected back-to-back across the extremities of that winding; the input circuit of the transistors in series with condenser $21k$ (cf. FIG. 1) is connected across an intermediate portion of the choke by way of intermediate taps thereof. Zener diodes $42k$ and $43k$ serve to limit the charging current of the condenser flowing into the bases of the associated transistors, thereby flattening the peaks of current I_{21} shown in graph (c) of FIG. 14. A similar effect is obtained by the circuit arrangement of FIG. 13 in which choke $17k$ is connected across two oppositely poled diodes $44k$, $45k$ whose junction is returned to the midpoint of the choke through a single Zener diode $46k$.

The system of my invention allows the use of low-cost linear transformers and eliminates power losses due to saturation. With the collector current and the collector voltage of the transistors lying generally in phase, switching losses are also minimal. No voltage spikes occur in the transistors so that no allowance need to be made for transients, the transistors being therefore operable at maximum rated collector current and emitter/collector voltage. Under no-load conditions, current flow will be very low since no saturation energy needs to be supplied; this yields very high conversion efficiencies at light loads.

Naturally, within the limits of compatibility, the several oscillators shown in different figures may be modified in light of one another, as by replacing NPN transistors

by PNP transistors and vice versa, by the use of other semiconductor elements such as controlled rectifiers, and by interchangeably using grounded collectors, emitters or bases. These and other modifications readily apparent to persons skilled in the art are intended to be embraced within the spirit and scope of my invention as defined in the appended claims.

I claim:

1. An oscillator comprising two semiconductor elements each having a first main electrode and two input electrodes including a second main electrode and a control electrode, said second main electrodes being joined together by a conductive connection; a load circuit including an output transformer with a primary winding connected across said first main electrodes and a source of direct current inserted between said conductive connection and the midpoint of said primary winding; an input circuit with two parallel branches extending from said conductive connection to said control electrodes; a pair of inductances serially connected in said branches; a feedback circuit including a secondary winding of said output transformer and capacitive means in series with said secondary winding, said feedback circuit being connected across said inductances for generating therein an alternating current flow in the rhythm of a similar current induced in said secondary winding upon alternate conduction of said elements whereby the latter are alternately driven to saturation and cutoff; and controllable impedance means in said input circuit for modifying said alternating current flow.

2. An oscillator as defined in claim 1 wherein said controllable impedance means forms part of a stabilizing network including a further secondary winding of said output transformer.

3. An oscillator as defined in claim 2 wherein said controllable impedance means comprises a transistor, said stabilizing network including a source of control signals for said impedance means energized from said further secondary winding.

4. An oscillator as defined in claim 3 wherein said source of control signals comprises a magnetic amplifier.

5. An oscillator as defined in claim 3 wherein said inductances form part of a secondary winding of an input transformer having a primary winding and a rectifier bridge in series with said capacitive means, said controllable impedance means being inserted in an output diagonal of said rectifier bridge.

6. An oscillator as defined in claim 1 wherein said controllable impedance means is inserted between said conductive connection and a common terminal of said inductances.

7. An oscillator as defined in claim 6 wherein said controllable impedance means comprises a transistor.

8. An oscillator as defined in claim 6 wherein said controllable impedance means comprises a transformer energized from a source of A-C signals.

9. An oscillator as defined in claim 1 wherein said controllable impedance means is connected between said inductances.

10. An oscillator as defined in claim 9 wherein said controllable impedance means comprises an adjustable phase shifter.

11. An oscillator comprising two semiconductor elements each having a first main electrode and two input electrodes including a second main electrode and a control electrode, said second main electrodes being joined together by a conductive connection; a load circuit including an output transformer with a primary winding connected across said first main electrodes and a source of direct current inserted between said conductive connection and the midpoint of said primary winding; an input circuit with two parallel branches extending from said conductive connection to said control electrodes; a pair of inductances serially connected in said branches; a feedback circuit including a secondary winding of said output transformer and capacitive means in series with said output transformer and capacitive means with said

secondary winding, said feedback circuit being connected across said inductances for generating therein an alternating current flow in the rhythm of a similar current induced in said secondary winding upon alternate conduction of said elements whereby the latter are alternately driven to saturation and cutoff; and a current-limiting circuit connected across the input electrodes of said elements in shunt with said inductances.

12. An oscillator as defined in claim 11 wherein said current-limiting circuit includes avalanche-type diode means connected to break down in response to a predetermined voltage drop across said inductances. 10

13. An oscillator as defined in claim 12 wherein said inductances are part of an autotransformer winding with intermediate taps connected across the series combination of said secondary winding and said capacitive means, said current-limiting circuit including sections of said autotransformer winding lying between the extremities thereof and said taps.

14. An oscillator as defined in claim 13 wherein said avalanche-type diode means comprises a pair of Zener diodes connected back-to-back across said extremities. 20

15. An oscillator as defined in claim 13 wherein said current-limiting circuit further includes a pair of rectifying diodes connected back-to-back across said extremities, said avalanche-type diode means being connected between the junction of said rectifying diodes and the midpoint of said autotransformer winding.
